Primary Examiner — Barbara Fox*Assistant Examiner* — Jamaal Rasheed(74) *Attorney, Agent, or Firm* — Green Mountain Innovations LLC; Alan Coté(57) **CLAIM**

The ornamental design for a bin with adjustable sides, as shown and described.

DESCRIPTION

FIG. 1 is a top, front, right side perspective view of a bin with adjustable sides showing the new design.

FIG. 2 is a front elevational view thereof, the rear view being a mirror image thereof.

FIG. 3 is a left side elevational view thereof, the right side being a mirror image thereof.

FIG. 4 is a top plan view of the bin with adjustable sides of FIG. 1.

FIG. 5 is a bottom plan view thereof.

FIG. 6 is an exploded perspective view thereof.

FIG. 7 is perspective view of the bin with adjustable sides of FIG. 1 showing environment.

FIG. 8 is a perspective view of the bin with adjustable sides of FIG. 1, shown in an alternate position; and,

FIG. 9 is another perspective view thereof, showing additional environment.

The two circular features on the lower right side depict portions of the bin with adjustable sides that form no part of the claimed design. The remaining broken lines depict environment that forms no part of the claimed design.

1 Claim, 5 Drawing Sheets
